COOKING UTENSIL OR SIMILAR ARTICLE

Morris Kaplowitz and Max Hirsch, New York,
N. Y., assignors to Federal Manufacturing &
Engineering Corp., a corporation of New York

Application September 29, 1949, Serial No. 5,226

Term of patent 14 years

(Cl. D81—10)

To all whom it may concern:

Be it known that we, Morris Kaplowitz and Max Hirsch, citizens of the United States, residing in the city of New York, Borough of Brooklyn, in the county of Kings and State of New York, have invented a new, original, and ornamental Design for a Cooking Utensil or Similar Article, of which the following is a specification, reference being had to the accompanying drawing, constituting a part hereof.

Fig. 1 is a perspective view of a cooking utensil or similar article in closed and locked position, showing our new design;

Fig. 2 is a sectional view, on an enlarged scale compared to the preceding view, taken on line 2—2 of Fig. 1; and

Fig. 3 is a perspective view of the device illustrated in the previous views, but showing the same in unlocked and open position.

We claim:

The ornamental design for a cooking utensil or similar article, substantially as shown and described.

MORRIS KAPLOWITZ.
MAX HIRSCH.
